UNITED STATES PATENT OFFICE.

CHARLES LE ROY STARK, OF WATSONVILLE, CALIFORNIA.

COUNTING DEVICE.

Application filed August 29, 1923. Serial No. 659,957.

This invention relates to a counting device and especially to a device of this character which is adapted to be attached to a fruit paring and coring machine. In apple growing districts where the major portion of the crop is dried, it is first necessary to pare and core the apples and then to slice the same before it is possible to sulphur and dry them. Machines run by individual operators are usually employed for paring and coring, as hand work is too slow and expensive. Some operators are paid by the day and others again by the box, the pay by the box being usually preferred by the workers or operators, as they can then work as slowly or fast as they like, but even so considerable trouble is encountered, that is, one box may contain fairly small apples and others large and so on, and some of the operators will, therefore, complain claiming that they are getting more than their share of small apples.

The object of the present invention is to avoid the above-mentioned difficulties by providing an arrangement whereby the workers may be paid by the number of apples cored and pared, that is, by paying the workers for instance ten cents a hundred or some similar amount. The object is accomplished by placing a counting device on each machine which will register each apple cored and pared, and simultaneously total the same, thus indicating at the end of the day's run the total number of apples handled by each operator.

Another object of the invention is to provide means for preventing fraudulent operation of the counting mechanism. Further objects will hereinafter appear.

One form which the invention may assume is shown in the following description and illustrated by way of example in the accompanying drawings, in which:—

Fig. 1 is a side elevation of an apple coring and paring machine showing the application of the counting device.

Fig. 2 is an enlarged front view of the counting mechanism.

Fig. 3 is a plan section taken on line 3—3 of Fig. 2.

Referring to the drawings in detail, A indicates in general a suitable form of apple coring and paring machine and B the counting mechanism employed in conjunction therewith. The machine proper consists of a main frame C, on one side of which is

journalled a shaft 2. Secured to one end of the shaft is a forkhead 3 which is adapted to receive the apples one by one; that is, the forkhead 3 rotates the apples during the 60 paring and coring operation and rotates in unison with the shaft 2. This shaft is a tubular shaft and a rod 4 extends therethrough. This rod will hereinafter be referred to as the core ejecting rod, and its 65 function and operation will later be described.

Secured on one end of the main frame is a stationary shaft 5 and journalled thereon are a pair of integral driving gears 6 and 7 70 which are rotated by means of a hand crank 8. The larger gear 7 intermeshes with a pinion 9 secured on the tubular driving shaft 2, while the smaller driving gear 6 intermeshes with a larger gear 10 herein- 75 after to be referred to as the cam gear.

Slidably mounted on one side of the frame is a carriage 11, this carriage being supported by means of a guide rod 12 which is slidably mounted in a pair of lugs 14^a 80 formed on the respective ends of the main frame C. The carriage carries the paring knife generally indicated at 14 and a coring knife which is generally indicated at 15. Reciprocable movement is transmitted to 85 the carriage through means of a cam 16 which is formed as a part of the gear 10.

The machine or mechanism so far described is old and well known, but a brief description has been submitted so that the 90 operation of the counting mechanism will be clearly understood.

The counting mechanism is enclosed in a casing generally indicated at B, this casing being secured between the two main uprights of the frame indicated at 95 17. Mounted interiorly of the casing is a standard counting and accumulating mechanism such as shown at 18, and extending from one side thereof is an actuating shaft 19. Secured on this shaft is an upwardly extending arm 20 and pivotally mounted on the upward end thereof as at 21 is a secondary arm or finger 22. Pivotally mounted 100 in one end of the casing B as at 23 is a bell crank which is provided with two arms generally indicated at 24 and 25. The upper arm 24 extends in under the upper finger 22, and the lower arm 25 is extended downwardly into alignment with a push rod 110 generally indicated at 26. This rod runs parallel with the driving shaft 2 and the

forkhead 3, and its purposes and functions will hereinafter be described.

Disposed vertically in the casing B on the other side of the counting and accumulating device indicated at 18 is a shaft 27. Carried by the upper end of the shaft is a crank arm 28 and pivotally mounted thereon as at 29 is an arm which consists of two sections such as indicated at 30 and 31. Formed on the lower end of the shaft is a radially extended lug or arm 32, and mounted in alignment therewith is a pusher rod 33, the opposite end of which is connected with a push-off lever 34 which is pivotally mounted on one end of the main frame as indicated at 35. The push-off lever is provided with two arms, the one indicated at 34 and a second arm such as indicated at 36. This arm is disposed in parallelism with the cam gear 10 and is intermittently engaged by a crank pin 37 formed on one side of the gear 10. The function and operation of the push-off lever or arm will hereinafter be described.

Before explaining the operation of the present machine and particularly the counting device, it must be understood that the main purpose of the present invention is to make a registration of each and every apple cored and pared, and to total the amount of apples handled during a day's run. Furthermore, I provide means for preventing fraudulent operation of the counting device. Having these features in mind, the operation will be as follows:

When it is desired to pare and core an apple, it is first necessary to grasp the apple with the left hand and to force it over the prongs of the forkhead indicated at 3. When the apple is thus forced onto the prongs, it will be thoroughly grasped and securely held and will at the same time force the core discharging rod 4 inwardly or in a direction towards the crank arm 8. This movement of the core removing rod is permitted as the shaft 2 is tubular and as the opposite end of the rod projects through the pinion 9. A head is formed on this end of the core removing rod and this head engages the arm 34 of the push-off lever and rocks it so that it will assume the position shown in Fig. 1. A second push rod is also actuated when the apple is applied, this rod being the one indicated at 26. A head is formed on the forward end of the rod as shown at 26^a, this head being engaged by the apple when it is forced over the forks. The pusher rod 26 is thus moved in the direction of arrow —a—, see Fig. 2 and a rocking movement is imparted to the bell crank. Arm 24 will thus swing upwardly and as its forward end engages the finger 22, this will be moved to assume a vertical position as indicated by dotted lines at 22^a.

After the apple has been forced into posi-

tion on the forkhead, it will only be necessary for the operator to grasp the hand crank 8 and to rotate the same. Rotation of the hand crank causes the gears 6 and 7 to rotate and similarly the gears 9 and 10, the gear 9 rotating the shaft 2 and the forkhead and the apple carried thereby, and the gear 10 rotating the cam which transmits a reciprocal movement to the carriage. The carriage will thus travel in a direction towards the hand crank 8 and as the paring knife 14 and the coring knife 15 are carried thereby, it can be seen that the apple will be pared and cored. During the return reciprocal movement of the carriage the paring and the coring knife are removed and the operation of paring and coring the apple is then completed. This is then removed and a new apple is applied. It is during the forward movement of the carriage that the counting mechanism 18 is actuated and this is accomplished as follows:

By referring to Fig. 3, it will be noted that the rear portion of the casing B is slotted as indicated at 40, and that the arm 30 normally assumes the dotted line position indicated at 30^a, thus as the carriage travels in a forward direction a portion thereof such as indicated at 41 engages the arm 30 and swings it in the direction of arrow —b— about its pivot 29. The opposite end of the arm 30 or that indicated at 31 will thus swing from the dotted line position indicated at 31^a in the direction of arrow —c—, and as finger 22 has already been swung to a vertical position into the path of movement of arm 31^a, it will be engaged by the arm and will be rocked in the direction of the arrow —d—.

The counting mechanism is actuated during this movement of the arms 20 and 22 and as the arm 31 swings over behind the arm 22, the arm 22 is released and returns to vertical position, it being held in horizontal position by a spring mechanism contained in the counting or accumulating device and not here illustrated.

The accounting mechanism has now been actuated and the apple which has by this time been pared and cored, has been accounted for. During the return stroke of the carriage, the paring knife and the coring knife are retracted and the core is at the same time ejected, this being accomplished by pin 37 engaging arm 36 and rocking the push-off lever in the direction of the arrow —e—. When the push-off lever rocks in the direction of arrow —e—, arm 34 engages the rod 4 and this is forced forwardly between the forkheads, thus ejecting the core which was cut by the knife 15. The apple may now be removed by hand and the fresh apple inserted, and the operation is repeated.

The pusher rod indicated at 33 is also connected to the push-off lever indicated at

34 as previously stated, and the rod 33 will therefore advance in unison with the core ejecting rod 4. The forward end of the rod 33 engages the lug 32 and it thus imparts a turning movement to the vertical shaft 27 so that it assumes the position shown in Fig. 3. This is of considerable importance, as it swings the arm 30 out or away from the slot 40 to a position where it cannot be tampered with, and as such prevents fraudulent operation of the counting mechanism. The pusher rod 26 serves the same function and a double check or prevention against unauthorized tampering or fraudulent operation is thus provided.

It must be remembered that if arm 30 always assumed the dotted line position shown in Fig. 3, it would not only be necessary for the operator to reach behind the machine and rock the arm 30 in the direction of arrow —b—. If he repeated this time and again, each movement would advance the register or counting mechanism one numeral. This is, however, prevented as a double check against fraudulent operation has been provided.

First of all, it is necessary to impart a rocking movement to the crank consisting of arms 24 and 25, so as to raise the finger 22 to vertical position. If this is not done and if finger 22 is permitted to remain in horizontal position as shown in Fig. 2, no operation of the counting mechanism will take place, as arm 31 will swing freely above finger 22 and will not operate the same.

It can therefore be seen that it is necessary to place an apple on the forkhead 3. This forces the pusher rod 26 in the direction of arrow —a— and thus imparts rocking movement to arm 24 causing the same to raise the finger 22 to vertical position. At the same time that the pusher rod 26 is actuated, the core ejecting rod 4 is also pushed backwardly by the apple and the opposite end thereof will therefore engage the push-off lever and swing this to the position shown in Fig. 1. This movement of the push-off lever will retract the pusher rod 33 causing it to release the lug 32. Shaft 27 will then rotate and swing the arms 30 and 31 to the dotted line position shown at 30^a and 31^a where it is ready to be actuated by the carriage arm 41 when it is correctly operated. Shaft 27 is only held in the full line position shown in Fig. 2 when the pusher rod 33 assumes its innermost position in engagement with the lug 32, but it rotates and assumes the dotted line position shown when the pusher rod 33 is retracted, this rotary movement being insured by a spring 44 attached to one end of the casing and having the opposite end secured to a crank arm 45 carried by the shaft. Arms 30 and 31 cannot rotate on their pivot 29 except when actuated by the carriage arm 41, as they are held in a predetermined

position ineoperative by means of a spring 46.

From the foregoing description, it can be seen that each and every apple placed in the machine which is pared and cored is registered and that the complete number of apples handled by the machine is totaled in the counting device indicated at 18. It can also be seen that the counting mechanism cannot readily be tampered with or in other words, fraudulently operated, as it would be necessary for the operator to actuate the pusher rods indicated at 4 and 26 and the arm indicated at 30. He, or she, would in other words have to use both hands to accomplish this, and it would very likely be detected by the foreman of the plant or other overseer. In fact, it would not pay an operator to fraudulently operate the counting mechanism, as rod 4 would have to be carefully forced backwardly between the forkhead 3. That is, the forward ends of the forkhead are very sharp and would very likely injure the finger tips of the worker, unless the operation of retracting the rod 4 was carefully undertaken. The forkhead ends are placed close together, thus increasing the difficulty in reaching the rod 4 and forcing it backwardly between the forks. In fact, the time taken in performing the fraudulent operation would be more than that of paring the apple. It may here be stated that a guard may be placed over the opposite end of the rod 4 and the push-off lever 34 and thus prevent operation of the rod from that end.

While the present mechanism and the means for operating the same have here been more or less specifically described, I wish it understood that various changes in the design and construction may be resorted to within the scope of the appended claims; furthermore, that the material and workmanship of the different parts employed may be changed to suit varying conditions.

Having thus described my invention, what I claim and desire to secure by Letters Patent is:—

1. In a machine of the character described, having a main frame, a reciprocating carriage mounted on the frame, a counting mechanism mounted thereon a forkhead for the reception of apples to be cored and pared, means for transmitting the reciprocating movement of the carriage to actuate the counting mechanism, and means cooperating with the forkhead to prevent actuation of the counting mechanism if an apple is not placed on the forkhead.

2. In a machine of the character described, having a main frame, a reciprocating carriage mounted thereon, a forkhead for the reception of apples to be cored and pared, a casing secured to the frame, a counting mechanism in the casing, an arm whereby

the counting mechanism is actuated, a finger pivotally mounted on said arm and normally assuming a horizontal position, means actuated by the placing of an apple on the forkhead for raising the finger to a vertical position, and other means actuated by the reciprocating movement of the carriage for engaging the finger to impart an oscillating movement to the forkhead and its supporting arm.

3. In a machine of the character described, having a main frame, a reciprocating carriage mounted thereon, a forkhead for the reception of apples to be cored and pared, a casing secured to the frame, a counting mechanism in the casing, an arm whereby the counting mechanism is actuated, a shaft vertically disposed in the casing adjacent the counting mechanism, an arm pivotally mounted on said shaft, said arm being engaged by the carriage during its reciprocating movement and being rocked thereby to cause said arm to engage the first named arm and to impart an oscillating movement thereto to actuate the counting mechanism, means cooperating with the forkhead for swinging the second named arm out of engagement

with the carriage thereby rendering the first named and second named arms inoperative if an apple is not placed on the forkhead. 20

4. In a machine of the character described, having a main frame a forkhead for the reception of apples to be cored and pared, a core ejecting rod cooperating therewith, a counting mechanism mounted thereon, and means actuated by the core ejecting rod for operating the counting mechanism. 35

5. In a machine of the character described, having a main frame a forkhead for the reception of apples to be cored and pared, a core ejecting rod cooperating therewith, a reciprocating carriage a counting mechanism mounted thereon, and means actuated by the core ejecting rod for operating the counting mechanism, an arm on the counting mechanism, a second arm pivotally mounted adjacent the same and engageable with the first named arm to rock the same to actuate the counting mechanism, the reciprocating carriage being engageable with the second named arm, and means for rendering the second named arm inoperative if an apple is not placed on the forkhead. 45 50

CHARLES LE ROY STARK.
